UNITED STATES PATENT OFFICE.

WALTER S. VINCENT, OF BURLINGTON, VERMONT.

DESIGN FOR A CAKE OF SOAP.

SPECIFICATION forming part of Design No. 16,397, dated November 24, 1885.

Application filed October 12, 1885. Serial No. 179,736. Term of patent 7 years.

To all whom it may concern:

Be it known that I, WALTER S. VINCENT, a citizen of the United States, residing at Burlington, in the county of Chittenden and State 5 of Vermont, have invented and produced a new and original Design for a Cake of Soap, of which the following is a specification, reference being had therein to the accompanying drawing.

10 My invention relates to a design for a soap-cake which is especially adapted to toilet or laundry purposes; and it consists in a cake of soap having the form of a rectangular or cubical prism having each of its corners so 15 truncated as to leave the opposite planes of the prism of the same size and form, and upon one or more of the planes is an isometric tetrahedral figure—that of a “diamond,” as it is commonly known.

In the drawing the figure is a perspective 20 view of my design of a cake of soap.

A represents the cake of soap, the shape of which is that of a prism having each corner *b* so cut away that the form of its sides *c*, faces *e*, and ends *d* shall be similar. Upon 25 one or more of these faces is a figure known as that of a “diamond.”

Having thus described my invention, I claim—

A design for a cake of soap, consisting of 30 the faces *e*, sides *c*, ends *d*, and cut-away corners *b*, as shown.

In testimony whereof I affix my signature in presence of two witnesses.

WALTER S. VINCENT.
